UNITED STATES PATENT OFFICE

2,262,305

SAFETY STOPPING MECHANISM FOR LOOMS

Aurelio Tellier, St. Simon, Drummondville, Quebec, Canada

Application May 14, 1940, Serial No. 335,100

3 Claims. (Cl. 139—337)

The present invention pertains to a novel safety mechanism for looms and is designed to stop the machine when one of the parts thereof takes an improper position, and thereby prevents further damage of the machine.

More particularly, the invention relates to the type of loom having one or more so-called blades carrying jack eyes. The blades are suspended from cables and are oscillated by a well known mechanism. Frequently one of the cables breaks, whereupon the blade is tilted and serious damage to the machine results if the mechanism is not stopped.

The object of this invention is to provide means for stopping the machine under these conditions. The invention comprises essentially a pivoted member mounted beneath the blade and engageable thereby when a cable breaks. This member is linked to a rod which is shifted laterally when the member is engaged by a falling blade. The rod in turn carries a stop that enters the path of a projection on the crank shaft for oscillating the blade. When the stop is struck by the projection, the rod is shifted longitudinally and in turn actuates a stop shaft which controls the running of the machine.

Preferably, two members of the character described are provided beneath the blade, one at each end thereof, so that one member or the other is engaged as a result of the breaking of either cable. These members are linked together and also to the rod as set forth above.

The invention is fully disclosed by way of example in the following description and in the accompanying drawing in which:

Figure 1 is a partial perspective view of a loom taken from the rear, and

Figure 2 is a detail cross section, illustrating also a multiple blade machine.

Reference to these views will now be made by use of like characters which are employed to designate corresponding parts throughout.

In Figure 1 are shown the usual pick sticks 1 having their lower ends 2 pivoted to a suitable support in the usual manner and their upper ends supporting the rocking comb 3. In rear of the comb 3 and parallel thereto is journaled a crank shaft 4 in the usual manner, the crank thereof being indicated by the numeral 6. Between the crank shaft and the comb is disposed a so-called blade comprising a rectangular frame 7 lying in a vertical plane and having wires 8 stretched vertically across the same. In the wires are formed the jack eyes 9. It will be understood that the blade 7 moves up and down and that

the comb is oscillated with the pick sticks 1 through the crank 6 and connecting linkage as will presently be described. Also, the lay swords support the shuttle box (not shown).

The comb 3 carries a clevis 10 in which is swivelled a block 11. On the crank 6 is mounted a bearing 12 joined to the block 11 by a pair of rods 13, whereby the movement of the crank is imparted to the comb 3.

The stopping mechanism constituting this invention includes a slidable rod 14 mounted horizontally and transversely of the comb 3 at one end thereof and supported in a pair of fixed brackets 15 and 16. The rear bracket 16 receives the rod in a slot 17 which permits transverse shifting of the rod as will presently appear. The rear end of the rod carries a stop 18 adapted to enter the path of a projection 19 on the bearing 12.

Beneath the blade 7 and near the ends thereof are mounted a pair of L-shaped supports 20 having one end 21 fixed to the floor or a suitable fixed part of a machine and the other end 22 also fixed in a convenient manner. On the horizontal leg 23 of each support is pivotally mounted an L-shaped member 24 having an arm 25 extending from one end and perpendicular to the plane thereof. A link 26 joins the rear end of the rod 14 to the nearer arm 25, and another link 27 joins the ends of both arms.

The stop 18 is normally drawn out of the path of the member 19 by a spring 28 joining the rod 14 to the bracket 16. At the forward end of the rod 14 is mounted the stop shaft 29 which controls the running of the machine. In this shaft is formed a lateral projection or crank 30 adapted to be engaged by a finger 31 formed on the forward end of the rod 14 when the rod is swung in the slot 7 and shifted lengthwise in the manner presently to be described.

In the operation of the device, it will be understood that the blade 7 descends by gravity, or in some cases by springs 32 joining its lower edge to the fixed structure, and is operated by cables 33 in the usual manner. The members 24 traverse the projected plane of the blade in order to lie beneath a plurality of blades 7', as in the modification illustrated in Figure 2.

In the event that one of the cables 33 breaks, the corresponding frame would tilt at one end and seriously damage the cloth in the making or even the machine, unless some provision is made for stopping the machine on such an occurrence. The stopping of the machine is accomplished by the present invention through the medium of the

members 24 disposed at the ends of the blade, one or the other of these members being engaged when one end of the blade drops because of a broken cable. The affected member 24 is obviously turned on the horizontal leg 23 of its support 20, turning also the corresponding arm 25 and pulling the links 26 and 27. The turning of the member 24 is assured by initially placing both members in a biased position as clearly shown in Figure 1.

When the links 26 and 27 are pulled, the rod 14 is swung in the slot 17, and the stop 18 enters the path of the projection 19. When the stop is struck by the projection, the rod 14 is pushed lengthwise, whereupon the finger 31 at the forward end thereof strikes the crank 30 and turns the shaft 29 to stop the machine.

Although a specific embodiment of the invention has been illustrated and described, it will be understood that various alterations in the details of construction may be made without departing from the scope of the invention as indicated by the appended claims.

What I claim is:

1. In a loom having a blade, a cable supporting said blade, a comb and a crank shaft for oscillating said comb, a member pivotally mounted beneath said blade and engageable thereby on breakage of a cable, a rod mounted for lateral and longitudinal movement adjacent to said crank shaft, a link connecting said member to said rod and adapted to move the rod laterally, a projection on said crank shaft, a stop on said rod arranged to enter the path of said projection on the lateral movement of said rod and to impart longitudinal movement to said rod on engagement by said projection, a stop shaft, a projection on said stop shaft, and a finger on said

rod arranged to engage said last named projection and actuate said stop shaft on longitudinal movement of said rod.

2. In a loom having a blade, a cable supporting said blade, a comb and a crank shaft for oscillating said comb, a pair of members pivotally mounted beneath said blade near the ends thereof and engageable thereby on breakage of a cable, a rod mounted for lateral and longitudinal movement adjacent to said crank shaft, a link joining said members and another link connecting one of said members to said rod and adapted to move the rod laterally, a projection on said crank shaft, a stop on said rod arranged to enter the path of

said projection on the lateral movement of said rod and to impart longitudinal movement to said rod on engagement by said projection, a stop shaft, and means on said rod for actuating said stop shaft on longitudinal movement of said rod.

3. In a loom having a blade, a cable supporting said blade, a comb and a crank shaft for oscillating said comb, a pair of U-shaped members pivotally mounted beneath said blade and engageable thereby on breakage of a cable, an arm

extending from each member, a rod mounted for lateral and longitudinal movement adjacent to said crank shaft, a link joining said arms and another link connecting one of said arms to said rod and adapted to move the rod laterally, a projection on said crank shaft, a stop on said rod arranged to enter the path of said projection on the lateral movement of said rod and to impart longitudinal movement to said rod on engagement by said projection, a stop shaft, and means on said rod for actuating said stop shaft on longitudinal movement of said rod.

AURELIO TELLIER.
